FOLDING BOX

Arthur Bennett, San Francisco, Calif.

Application June 2, 1937, Serial No. 145,983

2 Claims. (Cl. 229—30)

This invention relates to folding cardboard or paper boxes and cartons which are formed of cut-out and/or scored blanks, and the object of the invention is to provide means for more quickly and conveniently setting up such blanks to box form and securely hold them erected. Other advantages of the invention will appear from the following description and accompanying drawing.

In the drawing:

Figure 1 is a plan view of a cut-out folding box blank in process of being set up, and fully erected at the right-hand end.

Figure 2 is a perspective view of a portion of a non-cut out, but simply creased and scored box blank in process of being set up.

Figure 3 is a plan view of the right-hand corner of the flat blank of the box of Figure 2.

Figure 4 is a plan view of a scored and corner-cut box blank showing in dotted lines the set-up position.

Before describing the drawing in detail, it may be stated that folding boxes and cartons have heretofore been die cut or cut out in a variety of forms and scored along certain lines and/or creased so as to be easily folded to box form. Some of the forms adopted have interlocking tongues or flaps at the corners while others leave simple flaps or scored margins which are brought together to form the standing sides or walls of the box, and are thereafter glued together, or sometimes stapled. My improvement avoids the ordinary gluing or stapling of the corners or flaps to hold the box erected, or the use of interlocking tongues, yet makes a very strong joint and is performed in a fraction of the time heretofore required.

The improvement consists in applying to certain portions of the flaps or overlying portions of the box blank a coating of normally semi-tacky compound such as partially oxidized latex, which though not sticky enough to adhere to plain paper, cardboard, wood, glass or metal, will nevertheless adhere tenaciously to a similar coating when pressed thereagainst.

Such a coating on the flaps and/or selected portions of the blank enables the blanks to be piled up on one another face to back with no tendency to stick together, as the coated portions do not come face to face. A suitable coating for the purpose is made of a rubber or latex base suitably modified to yield a film or layer when spread on paper or cardboard which will have the semi-tacky surface nature required without being sticky.

It is well known that latex has the property of

adhering to itself when in the dry film state, if pressed together. This property, however, is not permanent, but in the course of a week or two gradually diminishes upon aging or exposure to air. Upon experiment, I discovered several means of prolonging this property by using various agents which seem to form a slight protective film over the latex layer, probably due to their being miscible with latex in the liquid phase but insoluble in the coagulated form, such as glycerin, glycols or glycol phthalate.

On further experiment, I found that a partially oxidized latex formed by treatment in the liquid phase had a greater tendency to stick to itself when dry by simple pressure, plus the advantage of retaining this property for a relatively long period of time, at least for six months under ordinary conditions. The partial oxidation of the latex also produced a product which could be used more sparingly than the unoxidized due to the fact that it possessed greater cohesive power. I find also that soluble cobalt salts used in conjunction with latex and/or an oxidizer give a suitable product for my purpose.

The following is the preferred formula for my coating compound:

Rubber latex, 33% solution	gallons	50
Hydrogen peroxide, 20% by volume	gallons	3
Cobalt nitrate	pounds	3½

Add the peroxide and cobalt nitrate to latex and stir in suitable mixer that is heated with steam pipes to about 175 degrees F. Considerable frothing will occur, but continue stirring for a period of three hours. At that time, add one more gallon of peroxide and stir for two hours.

Then add ½ gallon of concentrated ammonia and one pound of casein and stir until mixed. This adhesive can then be stored in drums until ready for use. (The ammonia and casein act as preservatives to prevent coagulation before using.)

To apply this adhesive to the flaps of the cartons or folding box blanks, any of the conventional means may be employed such as brushing, gumming with commercial gummers or spreading, and spread the work out to dry spontaneously before stacking, or dry by passing through a drier in warm air.

From the above it will be noted that if the folding boxes were to be erected within a few days or a week, a plain latex coating could be used, but for regular trade a six months or more life would be required. If the coated work is stored in a cool place protected from the cir-

culation of air, the effective life of the coating will be much extended.

In the drawing three common forms of folding box blanks are shown, that of Figure 1, that of Figures 2 and 3, and that of Figure 4, all coated at certain places with the semi-tacky compound described.

In Figure 1 the blank has a bottom 1, sides 2, ends 3, flaps 4 extending beyond the side walls, 10 and flaps 5 extending beyond the end walls. All walls and flaps are defined by suitable score marks 6 to facilitate bending along that line in setting up the box to form the vertical walls as shown at the right-hand end of the view.

15 The semi-tacky coating is shown at 7 on the upper faces of flaps 4 and 5, so that when the side walls are erected to the vertical as at 2' and the side flaps 4 folded to position of 4', wall 3 may be folded upward to lie against the outer 20 sides of flaps 4, and flap 5 may then be bent over and down inside the box as shown at 5' to embrace both flaps 4 between 3 and 5 and bring the coated face of 5 into direct contact with the coated faces of 4, and whereupon a 25 slight pressing of the folded members together instantly causes the two contacting coated surfaces to firmly adhere to one another so that they cannot be again separated without tearing the carton or box material.

30 The box corner of Figure 4 will be next described as it is simplest, consisting, in the blank form shown, of a bottom wall 8, side wall 9 with end flap 10 and end wall 11, all scored as at 6 as described for Figure 1. In this case, the upper face of end wall 11 is coated with the semi-tacky layer at 7 and the under side only of flap 10 is similarly coated, so that when wall 9 is erected to the vertical position 9' and flap 10 swung inward to position 10' its coated face will 35 be in confronting relation to coated area 7 of wall 11 as the latter is bent up to vertical position and will instantly lock therewith as the two coated surfaces are pressed together.

Figure 2 is a perspective view of a folding box blank having in the flat condition the scoring shown at 6 and 6' in Figure 3 and wherein the bottom of the box is designated 12, the side wall 13, end wall 14, end flap 15 and corner flaps 16, 17 and 18.

40 As the blank of Figure 3 is scored only but not cut at the corners, its method of folding, while common in the art, is not so simple as that of Figures 1 and 4, though easily understood by reference to the perspective view, Figure 2, wherein the left-hand corner is shown completely erected, and the members and score lines of the partially folded right-hand corner will easily be located by the same numerals as used in Figure 3.

45 From Figures 2 and 3 it will be seen that with this form of blank the semi-tacky coating 7 need only be applied to the upper surface of end walls and flaps 14 and 15 as these come face to face when the box is erected as indicated in Figure 2. The semi-tacky coating 7 may extend across the 50 upper faces of corner fold portions or flaps 16, 17 and 18, as 16 and 17 also come face to face with 15 and 14, and will make the extreme cor-

ners a trifle flatter, though it makes handling of the blank a bit more convenient if the coating is omitted from the corners.

5 By the improvement described, it provides a pile of flat blanks which will not stick together, yet are instantly ready for erecting into box form in a moment's time without use of glue, water or other solvent, or waiting for the ordinary glues and pastes to stick and dry, and also dispenses with the troublesome work of inserting flaps into slots as required for the interlocking flap type of folding boxes, yet provides a folding box which when erected in a moment's time is firmer than other types and resists unfolding even to destruction of the stock.

15 In my experiments I have found that the addition of the cobalt salt to natural, concentrated or partially oxidized latex tend to control the rate and degree of oxidation to such an extent as to cause the latex to possess far greater properties of adhesion to its own dried films. Moreover, films of latex, so treated with cobalt nitrate, maintain this adhesive property for prolonged periods of time while latex films, not so treated, have a tendency to resinify on exposure to air 20 and lose this property of being able to adhere together upon contact. Normal or natural latex loses this property of being "self sensitive" in about two weeks on exposure; partially oxidized latex loses it in about two months; but my tests indicate that cobalt treated latex retains this 25 property for periods upwards of six months. This improved treatment has valuable commercial usage in that boxes or cartons gummed with cobalt treated latex do not lose their adhesive properties and became useless when stored for future use.

30 Having thus described my invention and the manner of its use, what I claim is:

1. In a folding paper box or carton, the improvement which consists in providing those faces of the corners and walls of the blank which come face to face when the blank is erected to box form with a coating of semi-tacky adhesive containing rubber latex and cobalt nitrate, the degree of adhesiveness of the dried coating being insufficient to cause the blanks to stick together when piled in superimposed relation with coated surfaces against uncoated surfaces, but sufficient to cause immediate and substantially inseparable cohesion of the coated faces when simply pressed together in face contact.

40 2. In a folding paper box or carton, the improvement which consists in providing those faces of the corners and walls of the blank which come face to face when the blank is erected to box form with a coating of semi-tacky adhesive containing partially oxidized rubber latex and cobalt nitrate, the degree of adhesiveness of the dried coating being insufficient to cause the blanks to stick together when piled in superimposed relation with coated surfaces against uncoated surfaces, but sufficient to cause immediate and substantially inseparable cohesion of the coated faces when simply pressed together in face contact.

45 ARTHUR BENNETT.
